CHECK MARKING DEVICE

Richard I. Heller, Los Angeles, Calif.

Application October 5, 1938, Serial No. 233,375

5 Claims. (Cl. 101—22)

This invention relates to improvements in check marking devices, and it has for its object to improve the construction and operation thereof and particularly to provide an improved portable check marking device of the type or class shown and described in my co-pending application, Serial No. 144,322, filed May 21, 1937.

To these ends I have provided certain improvements in check marking devices as set forth in the following description, the several novel features of the invention being separately pointed out and defined in the claims at the close thereof.

In the accompanying drawing:

Figure 1 is a top plan view, full size, of my improved check marking device.

Figure 2 is an enlarged side elevation of the device shown in Fig. 1.

Figure 3 is an enlarged section on line 3—3 of Fig. 1.

Figure 4 is an enlarged side elevation showing the device in its open condition.

Figure 5 is an enlarged section on line 5—5 of Fig. 2.

Figure 6 is an enlarged end view of the device.

Figures 7 and 8 are enlarged sectional details on line 7—7 of Fig. 2 showing the marking mechanism in different positions.

The embodiment of my invention herein illustrated is a check marking device which is manually operable to impress protective markings upon bank checks, said device comprising a frame including a base 10 which may, if desired, be made with apertures 11, Fig. 1, for the reception of screws 12, Fig. 3, by means of which it may be fastened to the flap 13 of a check book, or to any other thing with which it may be associated as an attachment.

At the opposite sides thereof the base plate 10 is made with perpendicular side walls or ears 14, one at each side of said base. Between these walls or ears is a carrier, indicated generally at 15, for a plurality of independently rotatable toothed marking wheels 16.

The carrier 15 comprises a transversely disposed bar 17 provided at its opposite ends with radial arms 18 pivotally and slidably connected by pintles 19 to the side walls or ears 14 of base 10, said arms each being disposed upon the inner side of one of said walls or ears. The pintles 19 are rigidly and immovably fastened to the side walls 14 of the frame and as shown in Figs. 3, 7 and 8 they loosely occupy slots 20 formed longitudinally in arms 18 so that when the carrier occupies its closed position, shown in Fig. 3, it can be shifted to a limited extent on the frame

in a direction that is approximately perpendicular to the direction of the movement of cross-bar 17 when the carrier is swung up and down on pintles 19. The purpose of this will appear later.

As herein shown the carrier frame or body, 5 which includes cross-bar 17 and arms 18, is made from one piece of sheet metal and the cross-bar is formed approximately semi-cylindrical so as to inclose and cover the toothed marking wheels 16 thus affording protection to the hands of the 10 user and avoiding interference with the free operation of wheels 16 while marking a check.

Adjacent to the opposite ends of cross-bar 17, and aligned with the axis of the semi-cylindrical bar 17, the arms 18 are formed with apertures 15 21 which are permanently occupied by the reduced outer end portions of two spring pressed bolts 22 which are slidably mounted within a tube 23 disposed between arms 18 whose opposite ends abut the inner sides of said arms 18 and 20 which is maintained in this position by said bolts 22. The bolts 22 are yieldingly urged outwardly by a coiled spring 24 arranged within tube 23 between the inner ends of bolts 22, shoulders 25 on the outer end portions of the bolts 25 normally engaging the inner sides of the arms 18 to limit the outward movements of the bolts under the influence of spring 24.

When the carrier frame 17—18 occupies its lowermost position shown in Fig. 3 it will be 30 clear that it may be shifted horizontally relatively to the main frame 10—14 to an extent limited by the engagement of the opposite ends of slots 20 with pintles 19, as will be clear from Figs. 7 and 8.

When the carrier frame 17—18 occupies its closed position and is at the limit of its movement toward the right, Fig. 3, the outer reduced ends or trunnions of the bolts 22 occupy sockets provided in the side walls or ears 14 of the main 40 frame thereby to positively lock the carrier frame in its lower closed position, as will be clear from Fig. 7. One of these sockets is shown at 25 in Figs. 4, 5, 7 and 8 and said sockets may, as shown, be in the form of circular holes formed through 45 the side walls 14.

Between each pintle 19 and its complementary socket hole 25, and immediately adjacent to the latter, the inner side of the side wall 14 is made with a cam incline 26, Figs. 4, 7 and 8, leading 50 away from the hole which is effective to shift the bolt 22 from its projected carrier-locking position shown in Fig. 7, into the retracted inoperative position shown in Fig. 8. Thus while the carrier frame 17—18 occupies its closed posi- 55

tion farthest away from pintles 19, said frame is positively locked against upward displacement but when shoved rearwardly toward pintles 19 it is unlocked and free to be swung upwardly into the position shown in Fig. 4.

As the carrier frame 17-18 is swung upwardly toward the position shown in Fig. 4 the outer ends of the spring-pressed bolts 22 pass above the tops of the side walls or wings 14 and are again projected by their spring 24 so that it becomes necessary that they be again retracted in order to permit return of the carrier frame to its lowermost position again. In order automatically to retract the bolts 22 as the carrier frame is swung downwardly I form the inner sides of the upper portions of the side walls or ears 14 with cam surfaces or inclines 27, Fig. 5, against which the outer ends of bolts 22 strike as the carrier frame is lowered and by which the bolts are retracted until they register with and snap into the sockets 25.

Directly beneath or opposite the bank of marking wheels 16 the base plate 10 of the main frame is slotted at right angles with respect to the axis of tube 23 to provide a transverse series or row of rails alternate ones of which are bowed downwardly and form parts of a transverse groove 28 formed in the top side of base plate 10, and the others, 29 of which are horizontally straight and bridge or span the groove 28.

The elevated rails 29 are relatively spaced apart as shown to provide slots between them whereof some are occupied by the marking wheels 16. Thus the rails 29 support the check so that the latter will be punctured by the teeth of the wheels.

Upon the approach side of the wheels 16 and immediately adjoining the groove 28 is a transverse rib 30 which not only stiffens the base plate 10 but also bends a portion of the check C upwardly toward the marking wheels as the opposite end portion of the check is manually pulled upon in the direction of the arrow, Fig. 3, to draw said check through the device.

The groove 28 and rib 30 are less in length than the distance between side walls 14 so that the portion of base plate 10 immediately adjacent said side walls is horizontal and flat.

The marking wheels 16 are disposed on tube 23 in two groups, one to operate upon one line of the check and the other to operate upon another line thereof. These two groups are separated by a short ferrule 31 loosely mounted upon tube 23 while longer ferrules 32 loosely mounted upon the opposite end portions of tube 23 hold the two groups of wheels and ferrule 31 against axial displacement on said tube.

To use the above described marking device the wheel carrier 17-18 is raised into its elevated or open position shown in Fig. 4 to permit insertion of one end of the check C into the device. Then the carrier 17-18 is swung down into its lowermost position where it is automatically locked and held by the bolts 22 while the check is pulled forward by hand. As the check is pulled forward the wheels 16 are rotated and produce lines of protective perforations in the same. Usually the check is not pulled all of the way through the device and when such is the case and the lines of perforations have progressed the desired distance the check is released. This is accomplished by sliding the carrier 17-18 rearwardly on the main frame toward pintles 19 which causes the cams 26 to retract

bolts 22 so that the carrier can be raised into the position shown in Fig. 4.

What I claim is:

1. A marking mechanism of the character described, comprising a main frame including a base made with a series of check-supporting rails which are relatively spaced apart to provide slots between them; a carrier frame including a transversely disposed intermediate portion provided at its opposite ends with arms pivotally connected with said main frame adjacent to the opposite sides of said base so as to provide for up and down swinging movement of said carrier frame and also for lateral sliding movement thereof to a limited extent in a direction lengthwise of said slots; marking devices disposed above said base and rotatably supported by said carrier frame, said devices penetrating the check and projecting into said slots when said carrier frame occupies its lowermost position; means for locking said carrier frame in its lowermost position when it is shifted into check-marking position, and means for unlocking said carrier frame when it is slid laterally away from check-marking position.

2. A marking mechanism of the character described, comprising a main frame including a base made with a series of check-supporting rails which are relatively spaced apart to provide slots between them; a carrier frame including a transversely disposed intermediate portion provided at its opposite ends with arms pivotally connected with said main frame adjacent to the opposite sides of said base so as to provide for up and down swinging movement of said carrier frame and also for lateral sliding movement thereof to a limited extent in a direction lengthwise of said slots; marking devices disposed above said base and rotatably supported by said carrier frame, said devices penetrating the check and projecting into said slots when said carrier frame occupies its lowermost position; means for locking said carrier frame to said main frame when it is swung downwardly into check-marking position, and means for unlocking said carrier frame when it is slid laterally away from check-marking position.

3. A marking mechanism of the character described, comprising a main frame including a base made with a series of check-supporting rails which are relatively spaced apart to provide slots between them; a carrier frame including a transversely disposed intermediate portion provided at its opposite ends with arms pivotally connected with said main frame adjacent to the opposite sides of said base so as to provide for up and down swinging movement of said carrier frame and also for lateral sliding movement thereof to a limited extent in a direction lengthwise of said slots; marking devices disposed above said base and rotatably supported by said carrier frame, said devices penetrating the check and projecting into said slots when said carrier frame occupies its lowermost position; and latch mechanism for holding said carrier frame against upward movement when said frame is swung downwardly into check-marking position, said mechanism being manually operable to free said carrier frame for movement in the opposite direction.

4. A marking mechanism of the character described, comprising a main frame including a base made with a series of check-supporting rails which are relatively spaced apart to provide slots between them; a carrier frame including a trans-

versely disposed intermediate portion provided at its opposite ends with arms pivotally connected with said main frame adjacent to the opposite sides of said base so as to provide for 5 up and down swinging movement of said carrier frame and also for lateral sliding movement thereof to a limited extent in a direction lengthwise of said slots; marking devices disposed above said base and rotatably supported by said carrier frame, said devices penetrating the check and projecting into said slots when said carrier frame occupies its lowermost position; and latch mechanism for holding said carrier frame against upward movement when said frame is 10 15 swung downwardly into check-marking position, said mechanism being operated by lateral sliding movement of said carrier frame in one direction to free said frame for swinging movement thereof in the opposite direction.

20 5. A marking mechanism of the character described constructed in accordance with claim 4 wherein said arms are made near their free ends with apertures; wherein said transversely dis-

posed intermediate portion includes a tubular member whose opposite ends are aligned with the apertures of said arms; wherein said latch mechanism includes shouldered bolts slidably mounted within the opposite ends of said tubular member whose outer end portions slidably occupy the apertures of said arms, a spring within said tubular member disposed between the inner ends of said shouldered bolts and yieldingly urging the latter outwardly so that their shoulders normally 10 engage the inner sides of said arms to limit the outward movements of said bolts, sockets on said main frame with which the outer ends of said bolts co-act to hold said carrier frame in check-marking position, said sockets being each made 15 at one side thereof with a cam surface for retracting its bolt when said carrier frame is slid laterally in one direction thereby to free said frame for swinging movement thereof in the opposite direction, and wherein said marking 20 devices consist of marking wheels rotatably supported by said tubular member.
